UNITED STATES PATENT OFFICE

2,516,597

ELECTRIC VALVE COMMUTATION CIRCUITS

August Schmidt, Jr., Schenectady, N. Y., assignor
to General Electric Company, a corporation of
New York

Application September 9, 1949, Serial No. 114,750

3 Claims. (Cl. 321—11)

1

My invention relates to electric valve commutation circuits for electric discharge devices or electric valve means of the type employing ionizable mediums, such as gases or vapors.

In electric valve circuits such as multiple phase electric valve rectifying circuits, the problem of preventing arc-back is consistently present. One of the precautionary measures in preventing arc-back is to assure positive commutation between conduction of the current through one valve to conduction through another valve. This may be accomplished by assuring the early decay of the current in each valve just before it is to stop conducting. More specifically, diminution of arc-back frequency may be achieved by slowing down the rate of decay of anode current when the anode current approaches zero, so that a low value of anode current will be maintained for an appreciable time before initial inverse voltage is applied to the anode. During this time the high ionization density associated with normal load current will have an opportunity to diffuse and the reduced ion density at the time inverse voltage is first applied will result in a reduced probability of arc-back.

It is, therefore, an object of my invention to provide an electric valve translating apparatus including an improved means for assuring the early decay of the current in each electric valve immediately preceding its non-conductive period.

My invention consists essentially in an electric valve circuit employing auxiliary reactors connected with the electric valve apparatus supply transformer primary windings to obtain voltages at the electric valves which, because of their wave shape, assure good commutation.

For a better understanding of my invention, reference may be had to the following description taken in connection with the accompanying drawings, and its scope will be pointed out in the appended claims. In the drawings, Fig. 1 shows an embodiment of my invention wherein the electric valve supply transformer primary is connected in delta, and in Fig. 2 is shown a second embodiment of my invention wherein the electric valve supply transformer primary is connected in Y.

Referring now to the accompanying drawing, my invention is there illustrated as applied to a polyphase rectifying or translating system for energizing a direct current load circuit including a positive conductor 1 and a negative conductor 2, from an alternating current supply circuit 3. The electric translating apparatus also comprises an inductive network including a plurality

2

of electrically displaced windings which may be provided by a transformer 4, including primary windings 5, 6, and 7 and secondary windings 8, 9, 10, and 11, 12, 13.

To each of the secondary windings is connected an electric valve means 15, preferably of the type employing an ionizable medium such as a gas or a vapor, and including an anode 16, a cathode 17, and a control member 18, such as an immersion-igniter type control member constructed of a material such as boron carbide or silicon carbide, and which has an electrical resistivity relatively large compared with that of the mercury of the associated pool cathode. The electric valve means may also include a transfer or relieving electrode 19. In the interest of simplicity and clarity, only one of these electric valve means is shown in the diagram.

Control member 18 is connected through current limiting and stabilizing resistance 20 and unidirectional conducting device 21 to the excitation and control circuits which are indicated generally at 22. These excitation and control circuits are not shown in detail here, since they form no part of my invention. Any suitable control and excitation circuit may be used such, for instance, as that disclosed in Patent 2,362,294, issued on November 7, 1944, to A. H. Mittag, and assigned to the same assignee as the present application. Relieving electrode 19 is also connected to the excitation and control circuits through a current limiting reactor 23.

Connected with transformer primary windings 5, 6, and 7 are commutating reactors 24, 25, and 26. Each of these commutating reactors includes a main coil section 27 and a pre-saturating coil section 28. It will be seen in Fig. 1 that the main coil sections of the commutating reactors are respectively connected in series with the associated primary windings in a primary winding delta configuration, while the pre-saturating sections 28 are connected respectively in series with the supply lines from the supply circuit 3 to the delta. The current in the pre-saturating section is, therefore, line current, while the current in the remainder of the commutating reactor and transformer winding is delta current; thus, there is approximately a 30 degree phase displacement between the current in the presaturating section and the current in the main coil section of the commutating reactor.

Commutating reactors 24, 25, and 26 are of the saturable type and are saturated when the apparatus is conducting an appreciable value of load current but have substantially their full unsatu-

rated impedance when the current approaches zero. Thus, the commutating reactors modify the wave form of the current by prolonging the current at a small value just before it reaches zero. The result of this action on the primary current is to maintain a low value of anode current in the rectifier just before the application of inverse voltage to the rectifying element. Such an extended period of low anode current is beneficial to the rectifier because it permits diffusion of a considerable portion of the ionization resulting from preceding higher values of anode current and, thus, reduces the probability of arc-backs when inverse voltage is applied.

In order for the commutating reactors 24, 25, and 26 to be completely operative as above described, they must reach their unsaturated condition in each half cycle for an appreciable period before the occurrence of the current zero in their respective associated transformer secondary windings 9-13 in order that the current may be reduced for valve deionization. Normally, this would not occur because of the phase lag due to the magnetic hysteresis effect in the cores of these reactors. I, therefore, provide what I call a pre-saturating coil section in each of these commutating reactors which, in the embodiment of Fig. 1, are connected in series with the power supply lines to the delta configuration of the transformer primary windings 5, 6, and 7. Thus, each of these pre-saturating sections 28 carry line current, which has a slight phase advance over the current in the associated primary winding and main coil section. Thus, the combined magnetic result of the current in the main coil section and the current in the pre-saturating coil section of each of my commutating reactors is to advance the phase of the saturated and unsaturated conditions of the commutating reactors with relation to the current in the associated secondary windings, thus correcting for the undesirable lag due to hysteresis effect, as mentioned above. The current in each valve is thus reduced to a relatively small value for an appreciable period in each half cycle of valve conduction immediately prior to commutation. This period of low current permits the valve to partially de-ionize, which reduces the possibility of arc-back to a minimum.

In Fig. 2 is shown an alternative embodiment of my invention wherein the transformer primary windings and the main coil sections of the commutating reactors are connected in a Y configuration and the associated pre-saturating coil sections 28 are connected in delta at the center of the Y. The remainder of the system for Fig. 2 is similar to that shown for Fig. 1.

It will, therefore, be seen from the above description and disclosure that I have provided an extremely simple and economical means for improving commutation in electric valve translating apparatus which is particularly characterized by comparatively low first cost and ease of maintenance.

While I have shown and described my invention as applied to a particular system of connec-

tions and as embodying various devices diagrammatically shown, it will be obvious to those skilled in the art that changes and modifications may be made without departing from my invention and I, therefore, aim in the appended claims to cover all such changes and modifications as fall within the true spirit and scope of my invention.

What I claim as new and desire to secure by Letters Patent of the United States is:

10. In combination, a multiple-phase supply circuit, a load circuit, electric translating apparatus connected between said circuits and including a plurality of electric valve means and multiple-phase inductive apparatus having primary windings and secondary windings connected to said valve means, a commutating reactor for each of said primary windings having a main coil section connected in series with the 15 associated primary winding and a pre-saturating coil section connected to conduct a part of the current from another of said primary windings and thereby to conduct a total current having a phase displacement from the current to be 20 conducted in the associated main coil section and primary winding.
15. In combination, a multiple-phase supply circuit, a load circuit, electric translating apparatus connected between said circuits and including a plurality of electric valve means and multiple-phase inductive apparatus having primary windings and secondary windings connected to said valve means, a commutating reactor for each of said primary windings having a main coil section connected in series with the 25 associated primary winding, said primary windings and associated main coil sections being respectively connected in delta, each of said commutating reactors including a pre-saturating coil section connected in one of the supply lines to said delta and thereby adapted to carry a line current having a phase displacement from the delta current to be conducted in the associated main coil section and primary winding.
20. In combination, a multiple-phase supply circuit, a load circuit, electric translating apparatus connected between said circuits and including a plurality of electric valve means and multiple-phase inductive apparatus having primary windings and secondary windings connected to said valve means, a commutating reactor for each of said primary windings having a main coil section connected in series with the 25 associated primary winding, said primary windings and associated main coil sections being respectively connected in delta, each of said commutating reactors including a pre-saturating coil section connected in one of the supply lines to said delta and thereby adapted to carry a line current having a phase displacement from the delta current to be conducted in the associated main coil section and primary winding.
25. In combination, a multiple-phase supply circuit, a load circuit, electric translating apparatus connected between said circuits and including a plurality of electric valve means and multiple-phase inductive apparatus having primary windings and secondary windings connected to said valve means, a commutating reactor for each of said primary windings having a main coil section connected in series with the 30 associated primary winding, said primary windings and associated main coil sections being respectively connected in delta, each of said commutating reactors including a pre-saturating coil section connected in one of the supply lines to said delta and thereby adapted to carry a line current having a phase displacement from the delta current to be conducted in the associated main coil section and primary winding.
30. In combination, a multiple-phase supply circuit, a load circuit, electric translating apparatus connected between said circuits and including a plurality of electric valve means and multiple-phase inductive apparatus having primary windings and secondary windings connected to said valve means, a commutating reactor for each of said primary windings having a main coil section connected in series with the 35 associated primary winding, said primary windings and associated main coil sections being respectively connected in delta, each of said commutating reactors including a pre-saturating coil section connected in one of the supply lines to said delta and thereby adapted to carry a line current having a phase displacement from the delta current to be conducted in the associated main coil section and primary winding.
35. In combination, a multiple-phase supply circuit, a load circuit, electric translating apparatus connected between said circuits and including a plurality of electric valve means and multiple-phase inductive apparatus having primary windings and secondary windings connected to said valve means, a commutating reactor for each of said primary windings having a main coil section connected in series with the 40 associated primary winding, said primary windings and associated main coil sections being respectively connected in delta, each of said commutating reactors including a pre-saturating coil section connected in one of the supply lines to said delta and thereby adapted to carry a line current having a phase displacement from the delta current to be conducted in the associated main coil section and primary winding.
40. In combination, a multiple-phase supply circuit, a load circuit, electric translating apparatus connected between said circuits and including a plurality of electric valve means and multiple-phase inductive apparatus having primary windings and secondary windings connected to said valve means, a commutating reactor for each of said primary windings having a main coil section connected in series with the 45 associated primary winding, said primary windings and associated main coil sections being respectively connected in delta, each of said commutating reactors including a pre-saturating coil section connected in one of the supply lines to said delta and thereby adapted to carry a line current having a phase displacement from the delta current to be conducted in the associated main coil section and primary winding.
45. In combination, a multiple-phase supply circuit, a load circuit, electric translating apparatus connected between said circuits and including a plurality of electric valve means and multiple-phase inductive apparatus having primary windings and secondary windings connected to said valve means, a commutating reactor for each of said primary windings having a main coil section connected in series with the 50 associated primary winding, said primary windings and associated main coil sections being respectively connected in delta, each of said commutating reactors including a pre-saturating coil section connected in one of the supply lines to said delta and thereby adapted to carry a line current having a phase displacement from the delta current to be conducted in the associated main coil section and primary winding.
50. In combination, a multiple-phase supply circuit, a load circuit, electric translating apparatus connected between said circuits and including a plurality of electric valve means and multiple-phase inductive apparatus having primary windings and secondary windings connected to said valve means, a commutating reactor for each of said primary windings having a main coil section connected in series with the 55 associated primary winding, said primary windings and associated main coil sections being respectively connected in delta, each of said commutating reactors including a pre-saturating coil section connected in one of the supply lines to said delta and thereby adapted to carry a line current having a phase displacement from the delta current to be conducted in the associated main coil section and primary winding.
55. In combination, a multiple-phase supply circuit, a load circuit, electric translating apparatus connected between said circuits and including a plurality of electric valve means and multiple-phase inductive apparatus having primary windings and secondary windings connected to said valve means, a commutating reactor for each of said primary windings having a main coil section connected in series with the 60 associated primary winding, said primary windings and associated main coil sections being respectively connected in delta, each of said commutating reactors including a pre-saturating coil section connected in one of the supply lines to said delta and thereby adapted to carry a line current having a phase displacement from the delta current to be conducted in the associated main coil section and primary winding.
